UNITED STATES PATENT OFFICE.

JOHN SPEYER, OF CASCADE, MICHIGAN.

WRENCH.

SPECIFICATION forming part of Letters Patent No. 749,237, dated January 12, 1904.

Application filed December 27, 1902. Serial No. 136,793. (No model.)

To all whom it may concern:

Be it known that I, JOHN SPEYER, a citizen of the Netherlands, residing at Cascade, in the county of Kent, State of Michigan, have invented certain new and useful Improvements in Wrenches; and I do hereby declare the following to be a full, clear, and exact description of the invention, such as will enable others skilled in the art to which it appertains to make and use the same.

This invention relates to combination-tools; and it has for its object to provide a combined monkey-wrench and oil-can in which there will be a handle common to both the can and wrench and in which there will be no danger of discharge of oil from the can during the operation of the wrench.

Other objects and advantages of the invention will be understood from the following description.

In the drawings forming a portion of this specification, and in which like numerals of reference indicate similar parts in the several views, Figure 1 is an elevation showing a tool embodying the present invention. Fig. 2 is a section taken longitudinally through the tool.

Referring now to the drawings, the present wrench comprises what may be termed the "stem" 5, having a jaw 6 at one end projecting laterally beyond the stem.

Mounted slidably upon the stem 5, below the jaw 6, is a sliding jaw 7, and upon the stem below the sliding jaw are the laterally-projecting and vertically-spaced lugs 8 and 9. The upper lug 8 is perforated to receive the adjusting-screw 10, which latter engages threads in the longitudinal recess 11 of the sliding jaw, the lower end of the screw being engaged in the seat 12 in the upper face of the lower lug 9. Upon the screw 10 is fixed the thumb-nut 13, adapted for rotation with the screw to operate the latter to shift the sliding jaw. This portion of the wrench is of common construction.

In the lower end of the stem 5 of the wrench is a longitudinal recess 14, in the lower end of

which are the threads 15, and at the upper end of the recess is the axial pin 16, said pin passing through the washer 17, disposed against the inner end of the recess.

50

The handle 18 of the wrench is hollow and forms the body of an oil-can, this handle being cylindrical and of metal of sufficient stiffness to prevent compression thereof, excepting its lower end, which latter is of comparatively thin metal and is convex, so that it may be pressed inwardly of the body of the can to expel oil from the nozzle 19 of the can.

The nozzle end of the body of the can is exteriorly threaded, as shown, so that it may be screwed into the recess in the lower end of the stem of the wrench, the spout of the can being of such length that when the body is engaged with the recess the tip of the spout will lie against the washer 17, while the spout 65 will receive in its bore the pin 16. The pin and washer jointly prevent leakage of oil from the can, and should there be under some conditions a slight leakage the oil will be held in the recess 14 by reason of the washer 20, disposed upon the radial flange 21 of the body of the can.

70

By reason of the rigidity of the wall of the body of the can it will withstand any pressure to which it may be subjected in the operation 75 of the wrench, at which time pressure is not applied to the bottom of the can, and to protect the bottom against accidental pressure in the dropping of the wrench it may have a base-flange 22, extending below the convex 80 bottom, as illustrated.

It will be understood that in practice modifications of the specific construction shown may be made and that any suitable materials and proportions may be used for the various 85 parts without departing from the spirit of the invention.

What is claimed is—

A wrench having a stem formed of two parts, one part having a recess provided with threads, 90 a washer disposed against the inner end of the recess, and a pin secured to and extending from

the inner end of the recess and passing through the washer, the second part being hollow, threaded at one end and engaged with the threads of the recess removably, and a spout 5 at the threaded end of the handle adapted to lie within the recess of the stem and to receive the pin of the first-mentioned part.

In testimony whereof I affix my signature in presence of two witnesses.

JOHN SPEYER.

Witnesses:

LOUE PATTERSON,
JOHN M. STEKETEE.
